SAFETY GAS VALVE

Jasper P. Isaacs, Shamrock, Tex., assignor of
one-half to John Porter, Shamrock, Tex.

Application March 2, 1936, Serial No. 66,744

1 Claim. (Cl. 137—153)

This invention relates to safety gas valves especially adapted for gas supply lines between the latter and stoves or similar devices and has for the primary object, the provision of means which will automatically close the supply line to the stove when the pressure of the gas falls below a predetermined amount or to a pressure which would cause extinguishing of the flame of the stove so that on the return of the gas pressure to normal, the gas will be prevented from escaping at the stove.

With these and other objects in view this invention consists in certain novel features of construction, combination and arrangement of parts to be hereinafter more fully described and claimed.

For a complete understanding of my invention, reference is to be had to the following description and accompanying drawing, in which

Figure 1 is a side elevation illustrating a safety gas valve constructed in accordance with my invention.

Figure 2 is an end elevation illustrating the same.

Figure 3 is a sectional view taken on the line 3—3 of Figure 2, showing the valve in a closed position to stop the flow of gas therethrough.

Figure 4 is a view similar to Figure 3, showing the valve positioned to permit passage of gas therethrough.

Referring in detail to the drawing, the numeral 1 indicates a casing having inlet and outlet nipples 2 and 3. The inlet nipple 2 is connected to a gas supply line while the nipple 3 is connected to a line leading to a stove or similar device furnished with gas from the supply line. The inner end of the nipple 3 terminates into a cylinder 4 and one wall of the cylinder is provided with a port 5. The passage of the nipple where is communicates with the cylinder 4 is reduced to form a conical shaped seat 6 arranged adjacent to the port 5 and is adapted to be engaged by a weighted valve or plunger 7 pivotally connected to a link 8 which is in turn pivoted to one end of a bell crank lever 9. The lever 9 is pivoted in the casing and has pivoted to its other arm a link 10 provided with a notch 11. The link 10 is pivoted to a lever 12 and the latter is pivotally connected to the casing, as

shown at 13, and carries a valve element 14. The nipple 2 projects into the casing and forms a seat 15 to be engaged by the valve 14. A dog 16 is pivoted in the casing and engages the link 10 and is connected to a spring pressed finger piece 17 slidably supported by the casing whereby a person may effect pivotal movement of the dog. The dog when in engagement with the notch 11 locks the valve 14 against its respective seat and the plunger 7 in engagement with its seat, closing the passage between the nipples 2 and 3. A pressure on the finger piece 17 will disengage the dog from the notch.

In operation, the normal pressure of the gas through the casing 1 is sufficient to maintain the valve 14 away from its seat and the plunger in an elevated position, as shown in Figure 4. The valve and plunger, as shown in Figure 4, permit a free passage of the gas through the casing. However, should the pressure fall below a predetermined amount, the plunger 7 gravitates and closes the valve 14 and the dog engages the notch 11, preventing the valve 14 from again opening when the pressure of the gas increases or returns to normal. With the pressure of the gas at normal and the valve 14 locked in a seated position, the latter may be released by pressure applied to the finger piece 17.

While I have shown and described the preferred embodiment of my invention, it will be understood that minor changes in construction, combination and arrangement of parts may be made without departing from the spirit and scope of my invention, as claimed.

Having described the invention, I claim:

A safety gas valve comprising a casing, inlet and outlet nipples for said casing, a valve seat on the inlet nipple, a cylinder formed in the outlet nipple and having a port in communication with the interior of the casing, a pivoted valve in the casing to engage the seat, a plunger slideable in the cylinder, linkage between the plunger and valve and having a notch, a spring pressed dog pivoted in the casing to ride against the linkage and engage the notch when the valve is in a seated position to prevent opening of said valve, and a finger piece for effecting movement of the dog.

JASPER P. ISAACS.
